UNITED STATES PATENT OFFICE

169,291

FLYING DISK KITE

Angelo Spanvill, Brooklyn, N. Y.

Application October 29, 1952, Serial No. 22,030

Term of patent 7 years

(Cl. D34—15)

To all whom it may concern:

Be it known that I, Angelo Spanvill, a citizen of the United States, residing at Brooklyn, New York, in the county of Kings and State of New York, have invented a new, original, and ornamental Design for a Flying Disk Kite, of which the following is a specification, reference being had to the accompanying drawings, forming a part thereof.

In the drawing:

Fig. 1 is a top plan view of a flying disk kite, showing my new design;

Fig. 2 is a front elevational view of the same;

Fig. 3 is a side elevational view of the same;

Fig. 4 is an enlarged sectional view, taken on the line 4—4 of Fig. 1; and

Fig. 5 is a bottom perspective view of the flying disk kite.

I claim:

The ornamental design for a flying disk kite, as shown.

ANGELO SPANVILL.
